UNITED STATES PATENT OFFICE.

STANLEY KUTERBACH, OF PHILADELPHIA, PENNSYLVANIA.

ARMY-AMBULANCE.

Specification of Letters Patent. Patented Sept. 25, 1917.

1,241,402.

Application filed November 20, 1916. Serial No. 132,408.

To all whom it may concern:

Be it known that I, STANLEY KUTERBACH, a citizen of the United States, residing at Philadelphia, in the county of Philadelphia and State of Pennsylvania, have invented 5 certain new and useful Improvements in Army-Ambulances, of which the following is a specification.

This invention relates to new and useful 10 improvements in army ambulances.

The primary object of the invention is the provision of a wheeled ambulance partially bullet-proof, arranged for resiliently supporting a plurality of carrying stretchers, 15 the latter being retained in the proper positions inclosed within the vehicle.

A further object of the device is the provision of an ambulance readily movable from place to place, having bullet-proof 20 sides and a removable protecting top, superposed stretcher mounts being arranged between the sides with the upper mount shiftable for facilitating the use of the lower stretcher.

With these general objects in view and others that will appear as the nature of the invention is better understood, the same consists of a novel combination and arrangement of parts hereinafter fully described 30 and illustrated in the accompanying drawing and pointed out in the appended claims.

In the drawing forming a part of this application and in which like-reference characters designate corresponding parts throughout the several views,

Figure 1 is a side elevation of the device, Fig. 2 is a central longitudinal vertical 40 sectional view thereof,

Fig. 3 is a vertical transverse sectional view taken upon line III—III of Fig. 1,

Fig. 4 is an enlarged end elevation of a side portion of the device with the top removed and an end member arranged in position,

Fig. 5 is a perspective view of the wheel journaling frame, and

Fig. 6 is a perspective view of an end portion of a stretcher positioned upon one of the lower mounts of the ambulance.

The present invention comprises an ambulance consisting of a vehicle having an elongated body in the form of a wagon box 10, having a bottom 11 and upright sides 12, the latter being designed to be bullet proof.

An arched canopy 13, preferably formed of sheet-metal, although provided of can-

vas, if so desired, is removably arranged upon the sides 12, retained thereon by pins 14, carried by the top, fitting within staples 15 upon the said sides. A canvas or other 60 convenient form of end closure 16 may be arranged within either end of the body 10 if found desirable.

A transverse bolster 17 is secured beneath the bottom 11 of the body 10, having corresponding ends of leaf-springs 18 secured as at 19 to the laterally projecting ends of the said bolster, the said springs extending longitudinally of the body 10, with free end portions 20 adapted to receive seated thereon 70 the laterally projecting ends of a cleat 21, carried by the bottom 11.

A U-shaped frame 22 extends transversely beneath the body 10 spanning the latter with its side arms 23 projecting upwardly in sliding relation with respect to the sides 12, guide plates 24 being carried by the sides 12, between which plates the arms 23 are arranged. The frame 22 has a pair of ears 25 arranged at each end thereof, adapted for 80 the reception of substantially the central downwardly bowed portion of the springs 18, laterally projecting axles 26 being carried by the arms 23, for journaling the ground wheels 27 thereon. By this arrangement it will be seen that the springs 18, slidably attached to the frame 22 are supported by the wheels 27, while the body 10 is mounted upon the said springs, the latter being free to bend by reason of the sliding 90 connection of the spring ends 20 with the cleat 21, the body thereby being freely resiliently mounted upon the said traction wheels. The forward end of the body 10 is provided with any suitable form of handle 95 28, while a trunnion wheel 29 is arranged beneath the rear end of the body 10 upon a hinged bracket 30, having resilient connecting means 31, whereby the wheel 29 may swing in an arcuate path under the varying road conditions when the ambulance 100 is traveling along, either pulled forwardly or pushed rearwardly by means of the handle 28.

Stretcher mounts 32 are arranged within 105 the body 10, preferably in pairs, for resiliently supporting a plurality of stretchers, one above the other, the lower pair of stretcher supports comprise the U-shaped brackets 33 seated upon the bottom 11 and secured thereto by bolts 34, while channeled sides 35 thereof engage the body sides 12.

A slat 36 is shiftably arranged within the channels of the sides 35 resiliently mounted upon the springs 37, the stretcher 38 comprising side bars 39, and a connecting fabric 5 40 is readily positioned with the said bars 39, seated within, properly spaced apart, transverse grooves 41 formed in the slats 36. In this manner the stretcher 38 is arranged substantially horizontal within the body 10, 10 resiliently mounted by means of the springs 37, with the canvas 40 held taut, by retaining the bars 39 normally spaced apart in parallelism by the grooves 41.

The upper stretcher mounts comprise 15 channeled brackets 42, oppositely secured to the sides 12 of the body by means of bolts 43. These brackets are not connected together in accordance with the arrangement of the lower supports but have inwardly 20 projecting feet 44 upon which springs 45 are mounted for supporting cleats 46 with their free ends shiftably arranged within the channels of the brackets 42.

The cleats 46 are arranged with grooves 25 47 for receiving the side bars 39 of a stretcher. The side plates of brackets 42, at one side of the body 10, are slotted as at 48 for the reception of pintles 49, carried by the adjacent ends of the slats 36. By this 30 arrangement it will be seen that the upper slats 36 may be readily swung upwardly when the top 13 is removed, as best illustrated by dotted lines in Fig. 4 of the drawing, thereby allowing free access to the 35 lower slats 36, while the upper slats 46 are

free to move vertically when operatively positioned, by reason of the resiliency of the springs 45.

A serviceable ambulance is arranged for safely conveying persons upon stretchers, 40 the latter being supported so as to be substantially free from shocks and jars, affording comfortable beds for the occupants.

What I claim as new is:—

1. An ambulance comprising a body, supports arranged in different planes within the body, resiliently mounted slats carried by the said supports and formed with transverse stretcher bar receiving grooves, and 45 50 slideable pivotal connections between corresponding ends of the upper slats and the upper supports adjacent one side of the body.

2. An ambulance comprising a body, a stretcher mount arranged adjacent the bottom of said body, oppositely positioned 55 channeled brackets of U-form in cross section carried by the sides of the body above the said mount and having inwardly projecting feet, springs mounted upon the said feet, slats mounted upon the said springs 60 with their ends slidably arranged within the channels of the said brackets, the said slats having transverse grooves adapted for the reception of stretcher bars and placed apart substantially the width of a stretcher, 65 and slideable pivotal connections between the sides of corresponding ones of the said brackets and the adjacent ends of said slats.

In testimony whereof I affix my signature.
STANLEY KUTERBACH.

Copies of this patent may be obtained for five cents each, by addressing the "Commissioner of Patents, Washington, D. C."
